(57) **CLAIM**

I claim the ornamental design for a key arrangement for a handset, as shown and described.

DESCRIPTION

FIG. 1 is a front view of the key arrangement for a handset; and,

FIG. 2 is a perspective front view thereof.

The broken line showing of environment in the figures is for illustrative purposes only and forms no part of the claimed design.

1 Claim, 2 Drawing Sheets

FIG.1

FIG.2
